UNITED STATES PATENT OFFICE.

HARRY EBERT, OF FREDERICK, MARYLAND.

SHUTTER-LATCH.

1,158,657.

Specification of Letters Patent.

Patented Nov. 2, 1915.

Application filed February 12, 1915. Serial No. 7,761.

To all whom it may concern:

Be it known that I, HARRY EBERT, a citizen of the United States, residing at Frederick, in the county of Frederick and State 5 of Maryland, have invented new and useful Improvements in Shutter-Latches, of which the following is a specification.

This invention relates to shutter bowers, and has particular reference to an improved 10 means for automatically latching or locking the shutter when the same is swung into closed position.

The object of the invention is to provide a simple shutter latching means, the 15 major portion of which is mounted upon the sill of the window frame; a latching means which is of very simple construction, which may be economically manufactured, which is composed of relatively few parts occupying but small space; which is easily applied to the blind to take the place of the attachments at present in use; and a latching means which may be quickly released by the depression of one of the members thereof.

25 Other objects and advantages of this invention will be brought out in the following detail description of the present preferred embodiment of the invention, the same being illustrated in the accompanying drawings 30 wherein,—

Figure 1 is a horizontal section through the top of a window showing a blind in open position, and also showing the improved latching means applied thereto. Fig. 2 is a 35 similar view showing the blind in closed position, and showing the improved latch locked. Fig. 3 is an inside elevation of the same. Fig. 4 is a detail fragmentary view, showing in inside elevation the latch member released. Fig. 5 is a transverse section through the window frame, the latching plate, and blind; showing in side elevation the latch in the position of Fig. 4.

Referring to this drawing, wherein like 45 parts are designated by similar characters of reference throughout the several views, 10 designates a window frame having a sill 11 and supporting at one side a hinged blind 12. The blind 12 is provided with the 50 usual bracket 13 carrying a pivoted bower rod 14 which, as shown in Fig. 1, engages in a socket 15 mounted on the sill 11 to hold the blind 12 in open position.

Near the outer edge, and at the bottom of 55 the shutter 12, a hook 16 is mounted the same projecting inwardly and having a down-

wardly extending bill 17 the outer face of which is beveled, as shown to advantage in Figs. 4 and 5.

Mounted on the sill 11, and registering 60 with the hook 16, is a spring latch plate 18 having one end thereof returned in spaced relation beneath the plate to provide a base 19 for permanent attachment to the sill 11 and adapted to hold the plate 18 normally 65 and yieldingly in spaced relation above the sill 11, as shown in Fig. 3. As the plate 18 is a spring plate the same is provided near its outer free end with a regulating screw 20, the same passing down through the plate 70 and into the sill 11. The head of the screw 20 limits the upward springing of the outer end of the plate, and thus holds the plate in the desired horizontal position. As shown in 75 Figs. 1 and 2, the spring plate 18 is provided with a plurality of openings 21 adapted to receive the free end of the bower rod 14 to hold the shutter 12 in various closing positions. The hook 16 is so positioned upon the blind 12 that the bill 17 thereof 80 registers with one of the openings 21, as shown clearly in Fig. 2, so that when the blind 12 is closed the hook 16 engages in the said opening 21 of the spring latch plate 18 and locks the shutter 12 in closed position. 85

As the outer side or face of the bill 17 of the hook is beveled, the drawing of the blind into closed position forces the bill 17 against the spring plate, and the free end of the spring plate 18 is flexed down into the position shown in Fig. 4. This admits of the riding of the bill 17 over the upper face of the spring plate 18, and when the bill registers with the said opening 21, the plate by its inherent spring action rises to its normal 90 position and secures the bill 17 of the hook 16 in the opening. When it is desired to release the blind to open the same, all that is necessary to do is to depress the free end of the spring plate 18, such as by depressing 95 its outer end at the point 22, in order to move the plate down out of engagement with the bill 17 and admit the hook escaping the marginal edge of the opening 21. The blind 12 may now be pushed outwardly 100 into open position.

The hook 16 may be provided, as shown in the accompanying drawing, with upwardly extending fingers 23 and 24, the finger 23 serving as a hand grasp to swing 110 the shutter 12 into the desired position, while the other finger 24 serves not only as a

finger grasp but also as a support for the free end of the bowing rod 14 when not in use.

It will be noted that in the present preferred embodiment of the invention the hook may be a casting secured to the blind 12, while the spring plate may be made of a strip of flexible material suitably apertured and bent into the desired form. The base 19 is fixed to the sill 11 by a screw or the like, while its free end is held in the desired position longitudinally of the sill by the regulating screw 20. This screw 20 not only serves the purpose of holding the spring plate 18 from springing up above the hook 16, but also serves for preventing the plate 18 swinging laterally upon its base 19.

It is obvious that various changes may be made in the position, design, and detailed construction of the above-described embodiment of this invention without departing from the spirit thereof, such changes being restricted only by the scope of the following claims.

What is claimed is—

1. In combination with a window casing, and a shutter hinged thereto; a depending hook carried upon the inner side of the shutter and having a beveled edge facing inwardly when the shutter is closed; a spring plate secured at one end in spaced relation to the casing having an opening near its

free end in registry with the hook, said beveled edge of the hook being adapted to 35 strike the outer edge of the spring plate and to depress the free end thereof upon the closing of the shutter, said spring plate being adapted to spring up about the hook upon the passage of the hook into said opening, and a regulating screw carried by the casing engaging with the free end of the plate to limit the upward springing and the lateral swinging movement of the plate.

2. A shutter latch comprising a hook 45 adapted for securement to the inner side and at the bottom of a shutter, and having a depending beveled bill, a spring plate having an opening therein in registry with said bill and having one end returned beneath 50 the plate for securement to a window sill, a regulating screw carried by the sill and engaging the outer free end of the spring plate to limit the upward movement thereof and to prevent the lateral twisting of the 55 plate under tension of the hook, said plate having an extension on its free end adapted for engagement by the finger to depress the plate and release the hook.

In testimony whereof I have hereunto set 60 my hand in presence of two subscribing witnesses.

HARRY EBERT.
